CLAIM

The ornamental design for a perfume bottle, as shown and described.

DESCRIPTION

FIG. 1 is an elevational view of a perfume bottle showing my new design;

FIG. 2 is an elevational view looking from the right of FIG. 1;

FIG. 3 is a bottom plan view; and

FIG. 4 is a top plan view thereof.

The stippling in FIGS. 1 and 2 indicates contrasting shades of color.
